UNITED STATES PATENT OFFICE

REGINALD HENRY WHITE, OF TORONTO, ONTARIO, CANADA

PEDAL ATTACHMENT FOR AUTOMOBILES

Application filed August 4, 1932, Serial No. 627,517, and in Canada June 20, 1932.

My invention relates to improvements in pedal attachments for automobiles, and relates more particularly to a pedal attachment for the accelerator pedal-rod, and the object of my invention is to provide an attachment of the character set forth which will readily adjust itself to the position of the operator's foot, and which will remain in this adjusted position even though the operator's foot be moved out of contact therewith, and in the following specification and the drawing forming part thereof, I shall describe and illustrate my preferred form of invention and what I claim as new will be set forth in the claims forming part of this specification.

Fig. 1 is a vertical longitudinal central section through my pedal attachment showing the same attached to the upper portion of the accelerator pedal-rod, and Fig. 2 is a view of the underside of the sole plate.

In the drawing, like characters of reference refer to the same parts.

In many types of automobiles, the accelerator pedal-rod is provided at its upper end with a button-shaped head, and in operation since this head is usually made of metal friction of the boot thereagainst results in the wearing of these two elements. Frequently such wearing occurs on one side only of the head of the accelerator pedal-rod with the result that the foot of the operator has the tendency to slip to one side.

In order to overcome these disadvantages I have provided the invention I shall now describe:

2 is the sole plate and the same is suitably constructed to support a small mat 3 usually made of rubber or rubber compound.

40 Integrally formed with the said sole plate are lugs 4 which project below the underside of this sole plate.

Mounted between said lugs is a head 5 pierced to receive the pin 6 which is supported in the lugs 4. These parts are so combined so as to permit the sole plate 2 to have movement on the said pin.

The underside of the said sole plate is provided with spaced shoulders 7 which preferably project therebelow. These shoul-

ders are in alignment and are located substantially equi-distant from the axis of the pin 6. Located with its ends abutting the shoulders 7 is a bow-shaped resilient brake 8 which is constantly in frictional contact with the head 5. When the sole of the boot is placed on the sole plate 2, this sole plate will automatically assume the same angle to the floor of the motor car as that occupied by the sole of the operator's boot, and it will remain in this position by reason of the function of the brake already set forth.

Located intermediate the length of the head 5 is an arm 9 which is tapped to receive the upper end of the accelerator pedal-rod 10. 11 is a set screw mounted in a threaded hole formed in the outer end of the arm 9, and the function of this set screw is to key the head 5 to the accelerator pedal-rod 10, and to prevent the rotation of the said sole plate and head 5 around the axis of the said pedal-rod 10.

Considerable foot-fatigue is experienced by those who drive automobiles long distances, and it has been found that when the pressure of the foot against the head of the accelerator pedal-rod is spread over a surface substantially the same area as the sole of the boot, relief is had in that pressure against the sole of the foot is not concentrated on one point.

In case of repair, since the brake 8 is not fastened in place, the same can be replaced without expert help.

The width of the shoulders 7 as well as the brake 8 is such as to maintain the brake in position.

One of the objects of my invention is to produce an article of the class set forth which can be sold to those owning automobiles and readily attached to the accelerator pedal-rods of these cars after the head (not shown) has been removed from said pedal-rods. To do this requires that the design of my invention be such that the portion of the top of the sole plate 2 immediately above the accelerator pedal-rod occupy approximately the same position above the floor of the car as that occupied by the top of the button-shaped top the same is supposed to have had

before my sole plate has been combined therewith. Therefore I have found it necessary to locate the pivotal point of the said sole plate 2 to one side of the accelerator pedal-rod 10 and below the top thereof.

Obviously the lugs 4 are located equi-distant from a line passing centrally longitudinally of said sole plate. Also it will be evident that the said line will bisect the shoulders 7.

Various changes in construction may be made in that shown without departing from the spirit of this invention.

What I claim as my invention is:

- 15 1. An accelerator pedal attachment for automobiles embracing a sole plate; a pair of spaced lugs projecting below the underside thereof; a pair of spaced shoulders also located on the underside of the sole plate
20 and substantially equi-distant from the axis of said lugs; a head located between said lugs and adapted for association with an accelerator pedal-rod; means whereby said lugs and head are pivotally associated, and
25 a bow-shaped resilient brake resting in contact with said head and having its ends in contact with said shoulders.
2. In the pedal attachment for automobiles as set forth in claim 1, the provision
30 of an arm for said head provided with a tapped hole through its underside located to one side of the axis of said head.
